ADJUSTABLE AIR OUTLET UNIT

Birger Lärkfeldt, Odemsjo-Barnapp, and Lennart Widerby,
Jonkoping, Sweden, assignors to Aktiebolaget Svenska
Fläktfabriken, Nacka, Sweden

Filed Aug. 22, 1974, Ser. No. 499,860

Claims priority, application Sweden Feb. 25, 1974

Term of patent 14 years

Int. Cl. D23—04

U.S. Cl. D23—163

FIG. 1

FIG. 2

FIG. 3

FIG. 4

FIG. 5

FIG. 6

FIG. 1 is a perspective view of an adjustable air outlet unit showing our new design with air outlets in an extended position;

FIG. 2 is a perspective view with the air outlets in a retracted position;

FIG. 3 is a reduced bottom plan view thereof;

FIG. 4 is a reduced top plan view thereof;

FIG. 5 is a side elevational view with the outlets in the retracted position; and

FIG. 6 is a side elevational view with the outlets in the extended position.

We claim:

The ornamental design for an adjustable air outlet unit, substantially as shown and described.
